COKE OVEN WALL STRUCTURE

Filed March 29, 1928

Inventor:
Felix Totzek
By R. B. Sieger, Atty.

UNITED STATES PATENT OFFICE

FRITZ TOTZEK, OF STOPPENBERG, NEAR ESSEN-ON-THE-RUHR, GERMANY

COKE-OVEN-WALL STRUCTURE

Application filed March 29, 1928, Serial No. 265,588, and in Germany February 13, 1926.

This invention relates to improvements in coke oven wall structures, the object of the invention being to provide a gas or coke oven wall having flues therein and composed of two spaced courses of stretcher bricks and connecting and interposed header bricks so constructed and arranged that the joints between the header bricks, vertically, are broken to the extent that half the length of each header brick is imposed upon the next header brick below.

With the above and other objects in view, the invention consists in the construction, combination and arrangement of devices hereinafter described and claimed.

The accompanying drawing is a perspective of a portion of a gas or coke oven wall constructed in accordance with this invention.

In the figure of drawing, *a* designates the stretcher bricks and *b* designates the headers.

The stretchers *a* have recesses at the inner faces of the double wall, for interlocking with the transverse flue walls formed by the headers *b*. These stretchers alternate with bricks *b*, whose shape is roughly that of a hammer head, each brick *b*, having a projection *c*, whereby it is joined to one of the transverse bricks *b*. The limb or projection *c* merges into the body of the brick *b* with a rounded joint on both sides, forming a thick, strong root, so that there is practically no risk of the limb breaking away from the body of the brick.

Those parts of the bricks *b*, which lie within the courses, constitute stretchers, not headers, and they may be of the same length as the stretchers *a*, in which case the overlap throughout the wall amounts to half the length of the stretchers, the best bond which can be obtained.

Each header brick is of less length than the space between the outer surfaces of the courses and has a symmetrical end arranged between the opposing ends of two stretcher

bricks and extending to the outer surface thereof and also has a symmetrical opposite end arranged in the recesses in the inner surface of two stretcher bricks of the opposite course and terminates short of the outer surface of the last named stretcher bricks, and the contiguous header bricks of each course are reversely arranged, so that one such header brick extends to the outer surface of one course and the next such header brick of the same course extends to the outer surface of the opposite course.

Instead of using separate bricks *b*, the limbs of the bricks *b* may be made to extend right across the cavity, and this may be advantageous where the thickness of the wall is not such that the limbs would require to be inconveniently long for that purpose. The symmetrical shape of the bricks or blocks *b* is of advantage in that it reduces risk of deformation in the course of burning the bricks.

Having now particularly described and ascertained the nature of my said invention and in what manner the same is to be performed, I declare that what I claim is:—

1. A gas or coke oven wall having flues therein, said wall comprising courses of stretcher bricks certain of which have recesses on their inner sides at their meeting ends, said courses being spaced apart and said wall also comprising header bricks connecting said spaced courses, each header brick being of less length than the space between the outer surfaces of the courses having a symmetrical end arranged between the opposing ends of two stretcher bricks and extending to the outer surface thereof and also having a symmetrical opposite end engaged in the said recesses in the inner surface of two stretcher bricks of the opposite course and terminating short of the outer surface of the last named stretcher bricks, the contiguous header bricks of each course being reversely arranged so that one such header brick ex-

tends to the outer surface of one course and the next such header brick of the same course extends to the outer surface of the opposite course.

5 2. A wall as claimed in claim 1, wherein the limbs of the intermediate bricks merge into the bodies of said bricks with a rounded joint on each side, whereby a strong root is formed.

10 3. A wall as claimed in claim 1, wherein the intermediate bricks constitute stretchers of the same length as the plain stretchers.

In witness whereof I have signed this specification.
